UNITED STATES PATENT OFFICE.

JOHN LOFTUS, OF ALBANY, NEW YORK, ASSIGNOR OF ONE-HALF TO
PETER KINNEAR, OF SAME PLACE.

FEED-WATER INJECTOR.

SPECIFICATION forming part of Letters Patent No. 247,464, dated September 20, 1881.

Application filed July 5, 1881. (Model.)

To all whom it may concern:

Be it known that I, JOHN LOFTUS, of the city and county of Albany, and State of New York, have invented certain new and useful 5 Improvements in Feed-Water Injectors, of which the following is a specification.

My invention relates to improvements in injectors for supplying feed-water to steam-boilers; and the object of my improvements is to 10 facilitate a prompt and energetic action of the injector whenever it is started, and to render its action entirely automatic without recourse to the manipulations that are ordinarily required to effect the proper adjustment of the 15 several parts of the instrument whenever it is thrown out of use either by accident or design. This object I attain by means of the mechanism illustrated in the accompanying drawings, which form part of this specification, and in 20 which—

Figure 1 is a longitudinal section of my improved injector, showing the position of the several parts when the injector is at work; and Fig. 2, a like section in outline, showing the 25 position of the relief-valves while the injector is being started.

As ordinarily constructed injectors with automatic relief-valves are defective, for the reason that while the device is being started in 30 operation the inflow of the steam is checked and retarded by the contraction of the tapering passage between the steam-inlet and the relief-valve. This retardation causes the steam to set back and flow into the water-supply pipe, 35 and by its pressure therein the water is prevented from entering the injector until considerable time has been spent in adjusting the parts of the device that are hidden from the sight of the operator into positions that will 40 enable the apparatus to take water. To remedy this defect I provide my injector with an auxiliary relief-valve placed intermediately between the steam-inlet and the usual relief-valve, and form a full, free, and unobstructed 45 passage-way for the steam from its entrance at the inlet-opening to its escape through the auxiliary relief-valve, so that in starting the injector the flow of steam will be unretarded. By this free flow of steam sufficient vacuum is

instantly formed in the injector to enable it to 50 draw its supply of water at once, and the initial supply of water in passing through the unobstructed passage hereinbefore referred to acquires such velocity that, following the well-known law that imparts to a rapidly-moving 55 current of water an excessive force and power, and inclines it to always follow a straight course, it will be carried by its impetus into the coincident contracted passage, which, for the purpose of obtaining a proper operation of an injector, it is essential to interpose between the steam-inlet and the eduction-passage of the injector.

As represented in the drawings, my injector is composed of the following parts: 65

A is an adjustable nipple, to which the pipe for supplying the injector with steam is connected. Said nipple is provided with a coniform longitudinal passage, a , whose largest diameter is turned toward the entering current of 70 steam. The inner end of said nipple is reduced to form a conical nozzle, a' , so that the metal surrounding the inner end of the passage a will be reduced to a knife-edge.

B is the first section of the body of the injector. Said section is provided with a branch, b , for receiving an induction water-pipe, which connects with a suction-chamber, b' ; and extending from the latter there is a longitudinal passage, b^2 , which I preferably make cylindrical in form, and at its end next the chamber b' countersink it to form the conical enlargement b^3 , for receiving the end of the nozzle a' . The inner end of the passage b^2 is surrounded by a conical nozzle, b^4 . 85

C, the second section of the body of the injector, is provided with a vacuum-chamber, c , and a valve-chamber, c' , containing the steam-relief valve c^2 , which closes the escape-opening c^3 . Beyond the vacuum-chamber c a coniform longitudinal passage, c^4 , is formed, with its largest end turned toward the vacuum-chamber and its smallest end surrounded by a conical nozzle, c^5 . 90

D, the third section of the body of the injector, is provided with a chamber, d , and a valve-chamber, d' , containing the water-relief valve d^2 , which closes off the overflow-opening 95

*d*³. Beyond the chamber *d* a longitudinal education-passage, *d*⁴, is formed. Said passage is made of a conical form, with its smaller end turned toward the chamber *d*. The outer end 5 of the injector terminates in a screw-threaded end, *d*⁵, to which the feed-pipe leading to the boiler is connected.

The several sections of the injector are secured together in such manner that the passages *a*, *b*², *c*⁴, and *d*⁴ will coincide and range in a straight line. The nozzle *a'* passes entirely across the suction-chamber *b'* and enters the conical enlargement *b*³ in such manner that an annular passage will be formed between the latter and the nozzle *a'*, and the said annular passage may be either diminished or increased, as occasion requires, by screwing the adjustable nipple *A* into or out of the section *B*, to meet the requirement of the pressure of steam under 20 which the injector is to be used. When the nipple has been properly adjusted it should be secured in place by means of the jam-nut *a*². The nozzle *b*⁴ should extend about midway into the vacuum-chamber *c*, and the nozzle *c*⁵ should 25 be arranged in relation to the chamber *d* in a like manner.

The valve-chambers *c'* and *d'* are respectively provided with bonnets *c*⁶ and *d*⁶, each of the latter being provided with a central opening, 30 wherein the stem of the valve contained in its chamber is guided.

After the injector is fixed in place and properly connected to the boiler and to the water-supply by means of steam and water pipes, 35 its operation is as follows: Steam is admitted into the injector through the steam-inlet *a*, and when first admitted it passes freely through the passage *b*² and thence out of the escape-opening *c*³ and overflow *d*³, as indicated by the 40 arrows in Fig. 2. By this unresisted flow of the steam it attains such velocity that as it emerges from the nozzle *a'* it creates sufficient vacuum to cause the water to rise in the induction-pipe and enter the passage *b*² through 45 the annular opening between the nozzle *a'* and enlargement *b*³. It there, and during the entire

time the injector is operating, meets the current of inflowing steam, causing the latter to become condensed and producing sufficient vacuum to cause the relief-valve *c*² to fall into 50 its seat and close off the escape-opening *c*³. While passing through the passage *b*², before the relief-valve *c*² is closed, the water acquires so great a velocity that its impetus carries it into and causes it to pass irresistably through 55 the conical passage *c*⁴, chamber *d*, and education-passage *d*⁴, and from thence through the usual feed-pipe into the boiler.

From the foregoing it will be seen that the essential feature of my improvement is the introduction of the cylindrical passage *b*², vacuum-chamber *c*, and auxiliary relief-valve *c*² between the end of the nozzle *a'* and the conical passage *c*⁴ and relief-valve *d*². And by means of the cylindrical passage *b*² I provide 60 a free opening, through which the steam can reach the relief-valve *c*² without meeting the usual resistance presented by the conical-passage commonly used.

I claim as my invention—

1. In a feed-water injector, the passage *b*², vacuum-chamber *c*, and auxiliary relief-valve *c*², placed intermediately between the steam-inlet *a* and the relief-valve *d*², the passage *b*² being coincident and in the same line with the 75 passages *a*, *c*⁴, and *d*⁴, as and for the purpose herein specified.
2. In a feed-water injector, an auxiliary relief-valve, *c*², placed intermediately between the steam-inlet *a* and relief-valve *d*², as and for 80 the purpose herein specified.
3. In a feed-water injector, the combination, with the steam-inlet *a*, conical passage *c*⁴, chamber *d*, relief-valve *d*², and education-passage *d*⁴, of the passage *b*², vacuum-chamber *c*, an auxiliary relief-valve *c*², all constructed and arranged to operate as herein specified.

JOHN LOFTUS.
